CLAIM

The ornamental design for a charging handle, as shown and described.

DESCRIPTION

FIG. 1 is a top, front perspective view of an implementation of a charging handle;

FIG. 2 is a bottom, front perspective view thereof;

FIG. 3 is left side view thereof, the right side being a mirror image;

FIG. 4 is a right side view thereof, the left side being a mirror image;

FIG. 5 is a front view thereof;

FIG. 6 is a rear view thereof; and,

FIG. 7 is a top view thereof.

All broken lines are directed to environment and are for illustrative purposes only and form no part of the claimed design.
